PIPE CLAMP

William J. Fordon, New York, N. Y., assignor to
Rose Gringer, Bronx, N. Y.

Application December 20, 1939, Serial No. 310,143

1 Claim. (Cl. 138—99)

This invention relates to devices such as pipe clamps for stopping a leak in a pipe.

One object of the invention is to provide a pipe clamp having improved means adapted for causing the pipe clamp to reliably engage around a pipe that is very close to a wall or even in contact therewith.

Heretofore various types of pipe clamps have been known, which were of two general types, one comprising a band, and the other including a pair of plates. The band type has not been found to be very satisfactory for certain reasons, and hence the plate type is the one that is generally sold. However, the plate type always included locking or engagement means of one kind or another at opposite edges of the plates. Hence such a clamp could not be applied to a pipe that was close to a wall. In fact, it was often necessary to break away a part of the wall to afford clearance for the clamp.

This invention aims to overcome these difficulties and provides a device which is inexpensive, simple in use, durable, compact, convenient and reliable to a high degree, and the parts of which need not be separated or detached from each other in applying or removing the pipe clamp from a pipe.

Another object is to provide improved means for mounting a liner in the clamp to prevent the liner from slipping around while the clamp is being secured to a pipe, this mounting being accomplished in a particularly simple manner that is well adapted for quantity production.

Other objects and advantages of the invention will become apparent as the specification proceeds.

With the aforesaid objects in view, the invention consists in the combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a view in side elevation showing a device embodying the invention.

Fig. 2 is a view in front elevation thereof.

50 Figs. 3, 4 and 5 are sectional views taken on the respective lines 3—3, 4—4, and 5—5 of Fig. 1, with Fig. 4 showing the invention applied to a pipe.

55 Fig. 6 is a perspective view of one of the clamp plates.

Fig. 7 is a plan view of a liner element according to the invention.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device embodying the invention. This may include a pair of plates which, for inexpensive manufacture, are preferably exact duplicates of each other, whereby they can be stamped or cast with a single set of dies or with a single mold. By using these plates in reversed relation, as rights and lefts, they are brought in operative coordination with each other. However, other arrangements may also be used.

Each of these plates 11 may have a concaved pipe engaging portion 12 that is preferably curved, the same extending longitudinally of the plate. This curved portion may be adapted to engage a predetermined section of a pipe, and hence may engage around one-half, one-third or any other desired area of the pipe, with the radius of the curved portion being in accordance with the outside diameter of the pipe. Preferably allowance is also made for the interposition of a liner as hereinafter described to stop a leak in a pipe.

Extending along an edge portion 13 of the plate is a projection 14 which is preferably integral with the plate 11. Intermediate of the curved portion 12 and the projection 14 is a flange means 15 for mounting a tensioning device hereinafter described, as evidenced by the bolt holes 16. It will be noted according to Figs. 3 and 4 that the free edge portion 17 of the curved portion 12 extends somewhat above the plane of the flange 15. Preferably, the projection 14 constitutes a pivot 45 for which purpose it may be quite thin and hence is elongated for strength. To obtain maximum leverage, this pivot 14 is preferably disposed at the extreme outer edge at 13, and the bolt holes 16 are placed as close as possible to the curved portion 12. Simplicity of construction is best attained by arranging the pivotal projection 14 to extend above the plane of the flange 15 to a point higher than that of the free edge portion 17. Moreover, the pivotal projection is desirably po- 55

sitioned adjacent to an end of the flange 15. The bolt holes 16 are preferably irregular to non-rotatably secure a square shank portion or neck of a bolt. For reenforcing the curved portion 12, flanges 18 may be provided located at the opposite ends of the plate and leading into the flange 15. The flanges taper toward the free edge portion 17 so that the plate can engage a pipe 19 that may be disposed extremely close to a wall 20 as shown in Fig. 4.

Referring to Figs. 3 and 4, it will be perceived that the flange 15 affords a seat 21 for the bolt heads which is at an acute angle, so that the bolt heads exert maximum tension at 22, remotely from the pivot 14.

Formed in the curved portion 12 near the ends thereof are a plurality of holes 23 adapted to releasably engage the integral headed end projections 24 of a liner 25, shown in Fig. 7. This liner 20 may consist of rubber or other suitable sheet material that is adapted to seal a leak in a pipe, with the projections 24 serving to hold the liner in a predetermined relation to the plate 11 to prevent the liner from slipping while the device 25 10 is being applied to a pipe.

The foregoing description of the plates 11 applies to both plates, the latter being identical. The device 10 produced by a combination of these plates will now be described.

30 The device 10 comprises a pair of the plates 11, with their curved portions 12 confronting each other so as to engage around a pipe. When thus arranged the pivotal projection 14 of one plate seats on the flange 15 of the other plate, where-
35 by an interfitting disposition is obtained, with the projections 14 of the different plates being alined and serving as a single elongated fulcrum. Consequently the flanges 15 and the free edge portions 17 are normally spaced from each other
40 as shown in Figs. 3 and 4. Extending through the alined bolt holes 16 of the different flanges are the bolts 26 having square shank portions 27 fitted in adjacent holes, and having preferably round faced nuts 28, for tensioning the flanges 15
45 toward each other. These bolts may be arranged with their nuts at one side or another of the device. The liner 25 may likewise be engaged with either of the plates depending upon the side of the pipe at which the leak occurs.

50 In use, the device 10 is placed around a pipe so that the liner 25 covers the leak. Engagement is possible even with a pipe that is very close to a wall as shown in Fig. 4. Now the bolts 26 are tightened causing the plates 11 to pivot toward
55 each other about the pivotal means 14. Hence the curved portions 12 tightly grip the pipe and compress the liner because of the leverage of the intermediate tensioning means 26. Since the faces 21 diverge toward the curved portions 12,
60 the head and nut of the bolts will act most powerfully on the points 22, as remotely as possible from the pivots 14. Due to the use of a round faced nut 28, the same will not bite into the metal of the sloping surface 21 at 22. Upon actual test,

the device has been found fully satisfactory even at very considerable pressures of fluids.

The invention is thus seen to comprise confronting plates having at one end pipe engaging confronting curved portions and at the other end pivotal means, located preferably between the plates, and tensioning means wholly at one side of the curved portions intermediate of the latter and the pivotal means for exerting a leverage in drawing the curved portions toward each other about the pivotal means, and the curved portions having thin free ends wholly lacking in any obstruction to permit the device to engage a pipe that is very close to a wall.

It will thus be seen that I have provided a novel 15 powerful actuator means for pipe clamp jaw members located at one side of the jaws. While these jaw members are held in guided coaction by the pipe itself, it may be desirable to cause the actuator means to afford a guiding coordina- 20 tion as by the use of bolts or other pins or fulcrums as herein suggested to assure efficient operation of the actuator means. The most effective result is obtained by providing an actuator means operative at spaced points at least one of 25 which affords a pivotal action; at the other point, the action may be different or greater in degree, as by an axial or rotary motion of a member. The leverage principle affords a high degree of power with a simple structure and relatively lim- 30 ited strain with the several elements working simultaneously and in proportion with each other to avoid any possible binding and resultant breakage in applying the clamp. The simplest results are attained in the specific clamp shown, 35 with the bolts located between the pivot and the pipe clamp jaws, since a bolt is very strong in tension, whereas the pivot, whether made of cast or malleable iron, is strongest in compression, and when used in compression, requires no inter- 40 engagement other than mere contact, maintained by the guiding action of the bolts and of the pipe itself.

I claim:

A pipe clamp device comprising a plurality of 45 plates, each having a first curved section and a second laterally extending section, both sections being elongated in the direction of the axis of the curved section, each second section having a pro- 50 jection at its free edge constituting a pivot por-
tion, each second section having a plurality of bolt holes spaced along a line intermediate of the pivot portion and the curved section, said plates being duplicates of each other, said curved sections being arranged to embrace a pipe therebetween with the pivot portions lying along a line parallel to said axis and pivotally engaging their respective opposing second sections with the pivot portions lying between the said second sections, and bolts extending through said holes and having clearance with certain of said holes to permit the plates to pivot toward each other.

WILLIAM J. FORDON.
